SUCTION CLEANER

Harry B. White, Canton, Ohio, assignor to The Hoover Company, North Canton, Ohio, a corporation of Ohio

Application December 11, 1933, Serial No. 701,816

2 Claims. (Cl. 15-9)

The present invention relates to suction cleaners in general and particularly to improvements in the combination of an on-the-floor suction cleaning unit with a dusting tool unit. More specifically the invention comprises an improved dusting tool converter and its seat upon the suction cleaner body.

It is an object of the present invention to provide a new and improved suction cleaner provided with dusting tools. A further object of the invention is the provision of a new and improved dusting tool converter. Still another object is the provision of a suction cleaner in combination with dusting tools which are removably attached by new and novel securing means. These and other more specific objects will appear upon reading the following specification and upon considering in connection therewith the attached drawing to which it relates.

In the drawing in which a preferred embodiment of the invention is disclosed:

Figure 1 is a side view, with certain parts broken away and shown in section, of a modern suction cleaner embodying the present invention;

Figure 2 is a partial bottom view of the cleaner shown in Figure 1;

Figure 3 is a top view of the dusting tool converter;

Figure 4 is a sectional view upon the line 4-4 of Figure 2.

Figure 5 is a sectional view upon the line 5-5 of Figure 4.

The modern suction cleaner is a unit primarily designed for on-the-floor cleaning. To increase its range of usefulness the cleaner is so constructed that it can be combined with dusting tools which make the suction created by the unit effective at a point spaced therefrom. In the present invention a new and improved dusting tool converter is provided which is easily attached to the suction cleaner, and in particular to the suction-creating means thereof.

Referring again to the drawing a modern suction cleaner is shown comprising a nozzle 1, an air passageway 2 comprising side walls and a removable bottom plate which has been removed to permit the attachment of the dusting tool converter, a fan chamber 3, in which is rotatably mounted a suction-creating fan 4, and the exhaust outlet 5 through which the cleaning air drawn from the nozzle 1 and through the fan chamber is exhausted into the removably attached dust bag 6. A motor casing 7 is positioned immediately above the fan chamber 3 and houses

an unshown driving motor for the suction-creating fan, the extended shaft 8 passing through the fan chamber and into the air passageway 2 where it is provided with a pulley 9. In the normal operation of the cleaner in on-the-floor cleaning the pulley 9 drives the power-transmitting belt 10 which extends forwardly through the air passageway 2 into the nozzle 1 where it surrounds the rotatable agitator 11. The agitator comprises a body provided with suitable agitating elements which contact the surface covering undergoing cleaning. In the use of the cleaner with dusting tools the belt is disconnected from the pulley 9 as shown in Figure 1. The cleaner body is movably supported upon the front wheels 12, 12 and rear wheels 13, 13, the latter being pivotally mounted and provided with manual adjusting means, indicated generally by the reference character 14, by the use of which the nozzle may be raised or lowered relative to the surface covering. As in the usual suction cleaner of this type a pivoted handle 15 is provided which is suitably connected to the cleaner body and extends upwardly and rearwardly therefrom.

In the disclosure in the drawing the normal bottom plate of the machine which completes the air passageway from the eye of the fan chamber 3 to the mouth of the nozzle 1 has been removed and the belt 10 has been disconnected from the driving pulley 9. The entire suction of the suction-creating fan 4 is effective at the eye 16 and, by the attachment of the dusting tools at this point, cleaning air can be drawn therethrough instead of through the nozzle 1, the normal path. To accomplish this purpose the dusting tool unit is provided with a converter member, indicated by the reference character 17, comprising a main body portion having an opening corresponding in shape to the opening or eye 16. The walls of body 17 at the opening are adapted to contact the bottom of the fan chamber at eye 16, a surrounding shoulder 18 on the converter body forming a seat and limiting the extension of the body into the eye.

An outwardly extending shoulder or latch member 19 is formed on or secured to the body 17 at a point adjacent the opening and extends parallel to the bottom wall of the fan chamber 3 to a point at which it is contacted by a spring-pressed latch member 20, mounted on the bottom of the fan chamber. The latch 20 is normally spring-urged into locking position, as shown in Figure 2, and is provided with an extension 21 which is adapted to be grasped by the hand of the operator. By pulling on the element 21 the latch 20

can be moved against the normal force of the spring to permit the downward displacement of the shoulder or latch member 19 and the consequent removal of the converter 17.

- 5 To insure that the converter body will, at all times, be so placed relative to the fan chamber that the latch members 19 and 20 can cooperate there are provided two spaced lugs 22, 22 on the body which cooperate with and seat at the sides 10 of a projecting shoulder 23 on the bottom of the fan chamber. With the converter member seated in place the two lugs 22, 22 are positioned at the sides of the shoulder 23 and prevent rotational movement of the converter member relative to 15 the fan chamber, and also give a clear indication of how the two should be secured together. There is also secured to the inner wall of the body 17 of the converter a leaf spring member 24, the upper end of which extends upwardly and over the 20 top of the body 17 and overlies the inner surface of the fan chamber wall adjacent the opening 16. Member 24 cooperates with shoulder 19 and the spring-pressed latch member 20 in preventing the downward displacement of the converter member 25 from the fan chamber opening and in fact resiliently draws the body to the fan chamber.

The converter member 17 includes a transversely extending conduit or passageway 25 which is adapted to receive and seat the cleaner end of 30 the dusting tool hose 26. A spring-pressed detent 27 is provided which detachably secures the two parts together.

In altering the suction cleaner from an on-the-floor unit to an off-the-floor unit the operator removes the unshown but common bottom plate from the side walls of air passageway 2 and disconnects the belt 10 from the driving pulley 9. He then places the converter member 17 adjacent the eye 16 of the fan chamber with the leaf spring 35 member 24 overlying the inner side of the chamber wall of the adjacent eye and with the two lugs 22, 22 spaced at the sides of the locating shoulder 23. With the converter member so positioned the shoulder or latch 19 extends in close proximity

to the spring-pressed latch 20 which has been pulled to the side of the member 19 by the operator by means of a force exerted upon the element 21. Upon releasing the member 21 the spring force urges the member 20 below and into contact with the member 19 and forces that member and the entire converter in the direction of the fan chamber itself. The operator then needs only to secure the hose 26 to the conduit 25 of the converter member and the machine is ready 10 for off-the-floor cleaning.

I claim:

1. In a suction cleaner, a fan chamber having an eye, a dusting tool converter having a body formed with an opening and a conduit, said body being removably seated on said fan chamber with said opening alined with said eye, cooperating means on said chamber and body to aline said converter with said conduit extended in a particular direction, a resilient lug on said body at 20 said opening overhanging the interior face of said fan chamber adjacent said eye and functioning to draw said body to said chamber, and cooperating latch means on said chamber and body spaced from said overhanging lug to retain said 25 parts in operative relationship.

2. In a suction cleaner, a fan chamber having an eye, a dusting tool converter having a body formed with an opening and a conduit, said body being removably seated on said fan chamber with 30 said opening alined with said eye, cooperating means on said chamber and body to aline said converter with said conduit extended in a particular direction, a leaf spring on said body at 35 said opening extended thru said eye and into contact with the chamber wall, an outwardly extending latch member on said body spaced circumferentially around said opening from said leaf spring, and a manually operable spring-pressed latch on the bottom of said fan chamber 40 underlying said outwardly extending latch to removably lock said converter to said chamber.

HARRY B. WHITE.
